GRIPPING MACHINE

Victor J. Hugo, McKeesport, and John A. Miller, Brentwood, Pa., and Harry Ottinger, deceased, late of Washington, D. C., by Eulalia E. Ottinger, executrix, Washington, D. C., assignors to United States Steel Corporation, a corporation of New Jersey

Application September 6, 1949, Serial No. 114,214

4 Claims. (Cl. 81—17.2)

1

This invention relates to gripping machines, particularly machines for gripping articles while other operations are performed thereon.

Machines of the present invention are especially suited for gripping pipe lengths, for example, while threaded couplings or tool joints are applied thereto, although obviously machines that embody the same principles can be used for other purposes. Therefore, while we describe the machine in connection with gripping pipe, we do not wish to limit the invention to this particular use.

An object of the invention is to provide improved gripping machines which furnish a more positive and uniform grip on articles of varying dimensions within a tolerance range, than other machines with which we are familiar, and yet are of simple and rugged mechanical construction.

A further object of the invention is to provide improved machines for gripping articles in which the gripping elements are operated through a toggle linkage and a compensating mechanism, and in which the toggle linkage approaches its full extension when the elements are in gripping position irrespective of dimensional variations in the article, an arrangement which grips the article more positively and always with approximately the maximum mechanical advantage.

A further object of the invention is to provide gripping machines which have the foregoing improved features and in which the compensating mechanism automatically compensates for undersize dimensional variations in articles from the initial setting, thus insuring that the machine always grips articles with the same force and with approximately the maximum mechanical advantage.

In accomplishing these and other objects of the invention, we have provided improved details of structure, preferred forms of which are shown in the accompanying drawings, in which:

Figure 1 is a transverse vertical sectional view of an improved gripping machine which embodies features of the present invention;

Figure 2 is a top plan view of the machine;

Figure 3 is a side elevational view of the machine, partly in section; and

Figure 4 is a vertical sectional view similar to Figure 1, but showing a modification.

In Figures 1, 2 and 3 of the drawings there is shown a gripping machine which comprises a base 10 and a frame 12, preferably supported for longitudinal sliding adjustment on said base. Said frame carries gripping elements which in-

2

clude a fixed gripping block 13 and a movable gripping block 14. These blocks have gripping jaws 15 and 16 respectively, which are removable and replaceable to accommodate different sizes and shapes of articles. The mounting for the movable block includes guideways 17 which extend transversely of the frame. The movable gripping element may be advanced on said guideways to a gripping position in which its jaw 16 cooperates with jaw 15 to engage an article, such as a pipe length P, or it can be retracted so that the article can be removed or inserted.

Frame 12 has a laterally extending shelf 18 on which is mounted the mechanism for operating the movable gripping element. The shelf has upstanding brackets 19 which have trunnions 20 that carry a toggle operating fluid pressure cylinder 21, either hydraulic or pneumatic. A double-acting piston 22 is mounted for reciprocable movement in said cylinder and carries a downwardly extending piston rod 23. A toggle mechanism, hereinafter described, operatively connects the piston rod and the movable gripping block for advancing and retracting the latter. This arrangement furnishes a large mechanical advantage, so that the relatively low fluid pressures in the toggle operating cylinder are sufficient to operate the machine.

The toggle mechanism includes back and front toggle links 24 and 25. One end of the back toggle link is pivoted at 26 to brackets 19 of the frame. The other end of the back toggle link is pivoted at 27 to one end of the front toggle link and to the free end of piston rod 23. A set screw 28 is threadedly engaged in shelf 18 and furnishes a stop which engages the juncture between the toggle links when they are substantially at their position of alignment, but prevents their traveling beyond this position. The other end of the front toggle link is pivoted to a collar 29.

An internally screw threaded sleeve 30 is journaled in collar 29. The sleeve and collar carry cooperating latch means which normally prevent rotation of the sleeve. As illustrated, said latch means includes a dog 31 pivoted to the top of the collar and engageable with any one of a series of radial notches 32 in the end portion of the sleeve. A spindle 33 is threadedly engaged with sleeve 30 and carries a coupling 34, which is bolted to the movable gripping block.

It is seen that lowering piston rod 23 extends toggle links 24 and 25 toward their position of alignment with each other where their mechanical advantage approaches its maximum. This movement advances spindle 33 and movable

gripping block 14 and causes movable jaw 16 to cooperate with fixed jaw 15 for gripping article P. The effective length of the spindle may be adjusted by releasing the latch mechanism and turning sleeve 30. This adjustment fits the machine to different sizes of articles and supplements the adjustment obtainable by use of different sizes of jaws 15 and 16. Initially the machine is adjusted so that, when the toggle links are substantially fully extended and their juncture engages set screw 28, the movable gripping element is spaced from the fixed gripping element a distance required to engage an article of predetermined dimensions. For gripping articles in which the tolerance range is rather close, such as pipe lengths, this predetermined dimension can be the maximum oversize dimension within the tolerance range. For gripping articles in which wider dimensional variations are encountered, such as rough castings, this predetermined dimension can be something less than the maximum oversize dimension (e. g. the nominal dimension). The toggle links themselves then furnish compensating means for gripping oversize articles.

According to the present invention, the machine has mechanism for positively compensating for undersize variations in the dimensions of articles P from the predetermined dimension of the initial setting. This mechanism insures that a constant pressure in the toggle operating cylinder always causes the jaws to grip an undersize article with the same force and also that in gripping position the toggle links always are extended substantially to their position of alignment where their mechanical advantage approaches its maximum.

Figures 1, 2 and 3 show a compensating mechanism which includes a collar 35 keyed to spindle 33 and having an integral upstanding arm 36. Shelf 18 has a rearwardly extending bracket 37, to the top of which a fitting 38 is pivoted on a vertical axis (Figure 3). A compensating fluid pressure cylinder 39 is pivoted to fitting 38 on a horizontal axis. The two axes of pivoting thus furnish a universal mounting for this cylinder. A double-acting piston and piston rod 40 are mounted for reciprocable movement in cylinder 39 and the end of the piston rod is pivoted to the end of arm 36. The universal mounting of cylinder 39 enables this cylinder and piston rod 40 and collar 35 to travel with spindle 33 as the toggle links are extended or retracted.

In the starting position piston rod 40 is retracted, but it has sufficient play in the cylinder not to interfere with longitudinal movement of spindle 33. After the toggle links are substantially fully extended and their juncture engages set screw 28, the compensating cylinder 39 can be actuated to project piston rod 40, which thus rotates collar 35 and spindle 33. Dog 31 holds sleeve 30 against rotation; hence, when the spindle rotates, it advances along its threaded connection with said sleeve. This movement advances the movable gripping block and jaw until the latter grips article P with the established gripping pressure. The pressure in the toggle operating cylinder is sufficient to overcome the back pressure on the toggle links and prevent their buckling. Before the toggles are retracted, piston rod 40 and collar 35 are returned to their initial position.

Figure 4 shows a modified compensating mechanism in which the coupling 34a which connects spindle 33 and movable block 14 slidably re-

ceives said spindle. Said coupling extends outside frame 12 and carries a compensating fluid pressure cylinder 41. A double-acting piston 42 is mounted for reciprocable movement in said cylinder and carries a piston rod 43 which has a wedge-shaped end section 44. Coupling 34a and spindle 33 have vertical oversize passages 45 and 46 which receive said wedge-shaped section. Passage 46 through said spindle contains an upwardly tapering shim 47. When the toggle links are being extended, the wedge-shaped section of the rods acts merely to transmit movement of the spindle to the coupling and the movable gripping element. After the links are substantially fully extended and their juncture engages set screw 28, piston rod 43 can be lowered and the wedge surface of the rod cooperates with shim 47 to advance coupling 34a and the movable gripping element with respect to the spindle. Thus the gripping jaw grips article P with the established gripping pressure, as in the embodiment previously described.

From the foregoing description, it is seen that machines of the present invention transmit pressure applied to the piston in the main cylinder through a toggle linkage and that the mechanical advantage of this linkage approaches its maximum when the gripping elements engage an article whose dimensions equal the initial spacing of the gripping elements when the toggle links are extended. The compensating mechanism insures that the machine applies a grip of the same force to articles whose dimensions are undersize from this initial spacing. For gripping articles whose dimensions are oversize from this initial spacing, the toggle links do not become as fully extended but still are extended sufficiently to furnish a substantial mechanical advantage.

While we have shown and described only certain preferred embodiments of the invention, it is apparent that other modifications may arise. Therefore, we do not wish to be limited to the disclosure set forth but only by the scope of the appended claims.

We claim:

1. A machine for gripping articles whose dimensions vary within a tolerance range, said machine comprising a frame, fixed and movable gripping elements supported in said frame, a toggle operating fluid pressure cylinder pivoted to said frame, a double-acting piston and piston rod mounted for reciprocable movement in said cylinder, a toggle linkage pivoted to said frame and to said piston rod, a spindle interconnecting said toggle linkage and said movable gripping element and furnishing adjustment in the position said movable gripping element occupies when said toggle linkage is fully extended, a compensating fluid pressure cylinder, a double-acting piston and piston rod mounted for reciprocable movement in said compensating cylinder, and means operatively connected with said second named piston rod for advancing and reTRACTING said movable gripping element when said toggle linkage is substantially fully extended to compensate for dimensional variations in articles within the dimensional tolerance range for which the machine is adjusted.

2. A machine for gripping articles whose dimensions vary within a tolerance range, said machine comprising a frame, fixed and movable gripping elements supported in said frame, a toggle operating fluid pressure cylinder pivoted to said frame, a double-acting piston and piston

rod mounted for reciprocable movement in said cylinder, a toggle linkage pivoted to said frame and to said piston rod, a spindle interconnecting said toggle linkage and said movable gripping element and furnishing adjustment in the position said movable gripping element occupies when said toggle linkage is fully extended, a compensating fluid pressure cylinder universally pivoted to said frame, a double-acting piston and piston rod mounted for reciprocable movement in said compensating cylinder, and means operatively connecting said second named piston rod and said spindle for advancing and retracting said movable gripping element when said toggle linkage is substantially fully extended to compensate for dimensional variations in articles within the dimensional tolerance range.

3. A machine for gripping articles whose dimensions vary within a tolerance range, said machine comprising a frame, fixed and movable gripping elements supported in said frame, a toggle operating fluid pressure cylinder pivoted to said frame, a double-acting piston and piston rod mounted for reciprocable movement in said cylinder, a toggle linkage pivoted to said frame and to said piston rod, a collar pivoted to said toggle linkage, an internally screw threaded sleeve rotatably mounted in said collar, latch means normally connecting said collar and said sleeve and thus preventing rotation of said sleeve, a spindle threadedly engaged in said sleeve and coupled with said movable gripping element, said piston being adapted to advance and retract said movable gripping element through said toggle linkage, stop means engageable with said toggle linkage stopping movement thereof when said toggle linkage is in its position of substantially maximum mechanical advantage, a compensating fluid pressure cylinder universally pivoted to said frame, a double-acting piston and piston rod mounted for reciprocable movement in said compensating cylinder, and means operatively connecting said second named piston rod and said spindle for rotating said spindle relative to said sleeve and thereby advancing and retracting said movable gripping element when said toggle linkage is extended to its position of substantially maximum mechanical advantage to compensate for dimensional variations in articles within the dimensional tolerance range.

4. A machine for gripping articles whose dimensions vary within a tolerance range, said machine comprising a frame, fixed and movable gripping elements supported in said frame, a toggle operating fluid pressure cylinder pivoted to said frame, a double-acting piston and piston rod mounted for reciprocable movement in said cylinder, a toggle linkage pivoted to said frame and to said piston rod, a spindle pivotally connected to said toggle linkage, a coupling fixed to said movable gripping element and slidably receiving said spindle, said coupling and said spindle having aligned transverse passages, a compensating fluid pressure cylinder carried by said coupling, and a double-acting piston and piston rod mounted for reciprocable movement in said compensating cylinder, said second named piston rod having a wedge-shaped section received in said aligned transverse apertures for transmitting movement of said first named piston and said toggle linkage to said movable gripping element for advancing or retracting the latter, actuation of said second named piston advancing and retracting said movable gripping element and said coupling with respect to said spindle.
